(57) CLAIM

The ornamental design for a sprinkler head protector, as shown and described.

DESCRIPTION

FIG. 1 is a perspective view of a sprinkler head protector.

FIG. 2 is a top plan view thereof.

FIG. 3 is a bottom plan view thereof.

FIG. 4 is a front elevational view thereof.

FIG. 5 is a rear elevational view thereof; and,

FIG. 6 is a left side elevational view thereof, the right side elevational view being a mirror image of the left side view.
